UNITED STATES PATENT OFFICE.

ELIHU THOMSON, OF SWAMPSMOTT, MASSACHUSETTS, ASSIGNOR TO GENERAL ELECTRIC COMPANY, A CORPORATION OF NEW YORK.

CENTRIFUGAL PUMP.

1,112,238.

Specification of Letters Patent. Patented Sept. 29, 1914.

Application filed May 2, 1913. Serial No. 765,063.

To all whom it may concern:

Be it known that I, ELIHU THOMSON, a citizen of the United States, residing at Swampscott, county of Essex, State of Massachusetts, have invented certain new and useful Improvements in Centrifugal Pumps, of which the following is a specification.

The present invention relates to centrifugal pumps for water or other fluids and particularly to that type wherein a single impeller acts two or more times on the fluid, so that by means of a single impeller fluid at a relatively high pressure may be delivered.

For a consideration of what I believe to be novel, and my invention, attention is directed to the accompanying specification and the claims appended thereto.

In the accompanying drawings, which are illustrative of my invention, Figure 1 is a vertical section of one form of pump embodying my invention; Fig. 2 is a partial vertical section of the same on another diametrical plane; Fig. 3 is a sectional elevation on a plane transverse to Fig. 1, with the impeller removed; Fig. 4 is a partial view of the same, with the impeller in place.

Referring to the drawings, power is communicated in any suitable manner, as for example by means of the belt 1 and pulley 2, to a shaft 3 suitably journaled in a casing 4 and carrying an impeller, which comprises a web 5 and radial vanes 6 secured thereto. The sides of the vanes are tapered, and may be provided with shrouds 6^a if desired. These parts are carried on the outer portion of the web, leaving ample openings at the roots of the vanes for the water or other fluid to have access to them. The fluid to be pumped is supplied through a pipe 7 to a chamber 8 at the bottom of the casing, from which it proceeds through passages 9 to a small chamber 10 around the shaft and feeding said fluid to the inner ends of a certain group of vanes. In the interior of the casing, adjacent to the ends of the vanes, are several chambers and in the walls of the casing are curved ducts leading from said chambers to small independent chambers in the central portion of the casing, and communicating with the space at the roots of other groups of the vanes. In the drawings, the ducts are shown as cored out

in the material of the casing, their inner sides being closed by annular plates 11.

The course of the fluid is from the chamber 10 out through the radial impeller vanes to the lower chamber 12, where it divides into two portions, one passing up through the duct 13 to the chamber 14 and the other through the duct 13' to the chamber 14'. From these interior chambers 14, 14' it is fed again to the roots of the vanes and by them thrown radially outward into the next pair of outer chambers 15, 15'. From these it proceeds by the ducts 16, 16' to another pair of interior chambers, and so on until finally the two streams of fluid meet in the upper chamber 17 and pass into the delivery pipe 18. The advantage of this arrangement is that the fluid is taken in at the bottom of the pump casing and delivered at the top thereof, so that there is thus the greatest possible separation of the high pressure delivery end from the low pressure inlet end. It will be observed that in this form of pump, where the vanes are radial, it is immaterial in which direction the impeller is rotated; that is to say, it may revolve in either direction and will function equally well in both.

The partitions 19 which separate the ducts fit the impeller as closely as possible, and the impeller also fits the casing very closely, so as to prevent leakage between the high and low pressure sides of the pump. The thickness of the inner ends of the partitions should be a little less than the spaces between the vanes, so as to insure a constant flow of the fluid in a radial direction. It is also preferable to have the vanes break joint with each other in passing the partitions, so that while one set of vanes is transferring the column of fluid in the impeller from one inner chamber to its corresponding outer chamber, another set of vanes will be opposite a partition in one angular position and another set will be in still another angular position opposite another partition. In other words, it may be said that it is desirable to have the impeller's action with respect to the partitions be in different phases, so to speak, as regards the several partitions, thus causing an overlapping of the times when the impeller is discharging into both passages. This overlapping insures that at no time will there be a free passage

backward from the high pressure end to the inlet.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. A centrifugal pump having a single impeller, means for supplying fluid to the group of vanes occupying a certain angular position in the casing of said pump, and means for conveying the fluid discharged by said vanes to a succession of pairs of groups 20 of vanes annularly displaced from the first group and symmetrically arranged on either side thereof.

2. A centrifugal pump having a single impeller provided with vanes, a casing having inner chambers for supplying fluid to the roots of said vanes, outer chambers in said casing receiving the fluid from the tips

of said vanes, and ducts connecting each outer chamber with the inner chamber next in advance, said chambers being arranged in 30 pairs, so that the fluid will pass around the casing in two parallel streams from the inlet to the outlet.

3. A centrifugal pump having a single impeller provided with vanes adapted to receive fluid from both sides, a casing, an inlet conduit communicating with the lower end of the casing, an outlet conduit at the top of the casing, outer chambers and inner chambers in the casing, ducts connecting the lowest inner chamber with the inlet conduit, and ducts connecting each inner chamber with the outer chamber next in advance, the uppermost outer chamber communicating with the outlet conduit, whereby the 45 fluid will pass around the casing in two parallel streams.

In witness whereof, I have hereunto set my hand this thirtieth day of April, 1913.

ELIHU THOMSON.
